UNITED STATES PATENT OFFICE

150,399

DESIGN FOR A TRANSPORT TANK OR SIMILAR ARTICLE

Robert Bernstein, Omaha, Nebr.

Application July 22, 1946, Serial No. 131,809

Term of patent 14 years

(Cl. D14—3)

To all whom it may concern:

Be it known that I, Robert Bernstein, a citizen of the United States and a resident of Omaha, in the county of Douglas and State of Nebraska, have invented a new, original, and ornamental Design for a Transport Tank or Similar Article, of which the following is a specification, reference being had to the accompanying drawing, forming part thereof.

Figure 1 is a perspective view of a transport tank or similar article showing my new design.

Figure 2 is an enlarged end elevational view thereof, and

Figure 3 is a side elevational view of the transport tank.

The dotted line showing in Figure 3 of the drawing is for illustrative purposes only.

I claim:

The ornamental design for a transport tank or similar article, substantially as shown and described.

ROBERT BERNSTEIN.
